UNITED STATES PATENT OFFICE

FRANK R. BECKERT, OF SCHENECTADY, NEW YORK, ASSIGNOR TO GENERAL ELECTRIC COMPANY, A CORPORATION OF NEW YORK

LOUD-SPEAKER

Application filed September 15, 1924. Serial No. 737,660.

My present invention relates to sound reproducing devices and more particularly to devices capable of actuation by electric currents and adapted to reproduce faithfully and in large volume, sounds by means of 5 which the actuating currents have been produced.

In the most common type of such devices, a flat diaphragm rigidly supported at its periphery has been employed and this has been actuated by forces applied near the center. Such a diaphragm when actuated in this way may have several different natural periods 10 of vibration within the range of frequencies of the sounds to be reproduced. Consequently, any sounds which happen to be of the same frequency as any one of these natural periods 15 will be reproduced in greater relative volume than sounds having other frequencies.

I overcome this disadvantage to a large extent by applying the actuating force to the diaphragm at a plurality of points uniformly distributed over its area and provide means for applying substantially equal actuating 20 forces at the different points of application. By this provision, the greater part of the diaphragm is caused to move as a whole and substantially all of the internal stresses produced take place near its periphery. A diaphragm constructed and operated in this way 25 will not have the pronounced natural periods characteristic of the usual diaphragms, and such natural periods as it may have may be made to be greater than the frequency of any 30 of the ordinary sounds which are to be reproduced.

The novel features which I believe to be characteristic of my invention are set forth with particularity in the appended claims. 40 My invention itself, however, both as to its organization and method of operation will best be understood by reference to the following description taken in connection with the accompanying drawing in which Fig. 1 is 45 a vertical section of a device embodying my invention; Fig. 2 is another vertical section taken along the line 1-1 of Fig. 1; and Fig. 3 is a horizontal section taken along the line 2-2 of Fig. 2.

As indicated in the drawings, a base 1 is

provided having attached thereto an upright supporting member 2. The actuating mechanism comprises a pair of permanent magnets 3 and 4 each of which has opposing poles 5, 5 separated by a short air gap. The magnets are held in proper spaced relation to each other by a bridging member 6 to which they may be secured in any desired manner. The bridging member 6 is secured by means of 55 screws 7 to the bracket 8 which in turn is secured to the supporting member 2 by means of screws 9 and is vertically adjustable with respect thereto by means of screws 10.

A diaphragm actuating element or armature 11 is mounted in the air gaps of magnets 60 3 and 4 and between the two magnets is surrounded by actuating coils 12. These actuating coils are secured to a bracket 13 which in turn is secured to the support 2. A rigid dia- 65 phragm 14 is clamped between two rings 15 and 16. The lower ring 15 is supported from the base 1 by means of the supporting member 2 and a rod 17. The upper ring 16 is provided with a central opening 18 surrounded by a tube over which the horn 19 may be fitted. 70

The actuating element 11 is secured to the diaphragm 14 by means of four rods or struts 20, these rods being fastened by means of nuts, as indicated in the drawing, to four 75 points uniformly distributed over the area of 80 the diaphragm. The actuating element 11 is symmetrically disposed in the air gaps of the magnets so that when actuating currents are supplied to the coils 12 all parts of the element located in the air gaps will have substantially the same movement relative to the magnet poles and substantially equal driving 85 forces will be applied at each of the four 90 points on the diaphragm to which the rods 20 are attached.

The actuating element and diaphragm together form a rigid structure and substantially all of the area of the diaphragm enclosed within the points to which the driving forces are applied moves as a whole. The 95 only internal stresses produced in the diaphragm will be near the periphery and if the diaphragm has any natural periods they will in most cases be above the normal sound frequencies. 100

The operation of the device may in some cases be improved by the addition of a diaphragm damping device. This may comprise a spring member 21 which is secured to the ring 15 by means of screws 22 and which carries at its free end a pad 23 of felt or other resilient material. The pressure of this pad 23 against the diaphragm may be adjusted by means of a set screw 24, the end of which bears against spring member 21.

While I have shown and described only one embodiment of my invention, it is apparent that many modifications may be made in the structures used in carrying it into effect without departing from the scope thereof as set forth in the appended claims.

What I claim as new and desire to secure by Letters Patent of the United States, is,—

1. A sound reproducing device comprising 20 a diaphragm, a magnet having a pair of opposing poles separated by a short air gap and an armature located in said air gap and spaced from said diaphragm, said armature being supported from a plurality of points on 25 said diaphragm.

2. A sound reproducing device comprising a diaphragm, means for vibrating said diaphragm, said means including a magnet, said magnet comprising an armature supported at 30 a plurality of points on said diaphragm, and a pair of pole pieces cooperating with opposite sides of said armature, said armature being adapted to exert a driving force on said diaphragm.

3. A sound reproducing device comprising a diaphragm, a magnet having a pair of opposing poles separated by a short air gap, an armature located in said air gap and supported from a plurality of points on said diaphragm, and an actuating coil surrounding 40 said armature.

4. A sound reproducing device comprising a diaphragm, a pair of magnets each of which has a pair of opposing poles separated by a 45 short air gap, and an armature located in the air gaps and between the opposing poles of said magnets said armature being supported from a plurality of points on said diaphragm.

5. A sound reproducing device comprising a diaphragm, a pair of magnets each of which has a pair of opposing poles separated by a short air gap, and an armature located in the air gaps and between the opposing poles of 55 said magnets, said armature being adapted to exert substantially equal driving forces on said diaphragm at a plurality of different points.

6. A sound reproducing device comprising 60 a diaphragm, a pair of magnets each of which has a pair of opposing poles separated by a short air gap, and an armature located in the air gaps of said magnets and supported from a plurality of points on said diaphragm, said 65 armature being so constructed and arranged

that when actuated all parts thereof in the air gaps will have substantially the same relative movement with respect to the magnet poles.

7. A sound reproducing device comprising 70 a diaphragm and an armature adapted to actuate said diaphragm, said armature being spaced from but rigidly connected at a plurality of points to a plurality of corresponding points on said diaphragm.

8. A sound reproducing device comprising 75 a diaphragm and an armature adapted to actuate said diaphragm, said armature being spaced from but rigidly connected at a plurality of points to a plurality of corresponding points uniformly distributed over the 80 area of said diaphragm.

9. A sound reproducing device comprising 85 a diaphragm, and an armature adapted to actuate said diaphragm, said armature comprising a single member arranged in a plane substantially parallel to the plane of said diaphragm and being rigidly connected to said diaphragm at a plurality of points.

10. A sound reproducing device comprising 90 a diaphragm, and an armature adapted to actuate said diaphragm, said armature comprising a single member spaced from but rigidly connected at a plurality of points to a plurality of corresponding points on said diaphragm, and actuating means for said armature so arranged that the armature is adapted to exert substantially equal driving forces on said diaphragm at all of the points 95 of connections thereto.

11. An electromagnetic sound reproducer 100 comprising in combination a casing, permanent magnetic means, electromagnetic means located between said permanent magnetic means, a freely floating armature positioned within both of said means, a diaphragm in said casing and a connection between opposite ends of said freely floating armature and said diaphragm whereby vibrations transverse to the axis of said electromagnetic 105 means may be imparted to said diaphragm.

In witness whereof, I have hereunto set my hand this 13th day of September, 1924.

FRANK R. BECKERT.
